DESCRIPTION

FIG. 1 is a perspective view of the rocker switch for an electrical device of embodiment one showing our new design;

FIG. 2 is a front elevation view thereof;

FIG. 3 is a right side elevation view, the left side elevation view being a mirror image thereof;

FIG. 4 is a top plan view of the switch thereof; and,

FIG. 5 is a perspective view of FIG. 1 according to a second embodiment wherein the oval shape detail of the front surface is omitted.

In FIGS. 1-5, the broken line illustration of the environmental structure forms no part of the claimed invention.
